ELECTRIC IRON HANDLE CONSTRUCTION

Original Filed April 2, 1945

UNITED STATES PATENT OFFICE

2,662,317

ELECTRIC IRON HANDLE CONSTRUCTION

John R. Gomersall and Murray Ireland, Elgin,
Ill., assignors to McGraw Electric Company,
Elgin, Ill., a corporation of Delaware

Original application April 2, 1945, Serial No.
586,099, now Patent No. 2,585,928, dated Feb-
ruary 19, 1952. Divided and this application
February 18, 1952, Serial No. 272,222

6 Claims. (Cl. 38—90)

1

Our invention relates to sadirons and particularly to electrically heated sadirons. The same constitutes one of the various inventions originally included in our prior copending application Ser. No. 586,099, filed April 2, 1945, now Patent No. 2,585,928, granted February 19, 1952, to which the present application is related as a divisional application.

As conventionally constructed electric iron handle includes a horizontal grip portion of non-metal heat-insulating material adapted to be held by the hand for ironing operation and integral back and front supporting posts for mounting the grip portion on the body of an electric iron. It is common also to mount a manual adjusting knob or wheel on the front end of the handle grip portion for adjusting thermostatic heat control mechanism within the body of the iron which controls operation of the iron electric heating element and to connect the adjusting knob or wheel with the control mechanism by actuating mechanism housed in the front handle supporting post.

An object of the present invention is to provide an improved handle construction for irons which reduces the transmission of heat to the grip portion of a handle without sacrificing the main advantages of the above-described prior handle construction.

Another object of the invention is to provide an improved handle construction having only a single handle supporting post at the back and with independent structure adjacent the front end of the handle grip portion where commonly there is a front supporting post integral with the handle.

Another object of the invention is to provide an improved iron handle construction which permits a manual adjusting knob or handle to be mounted separately from the front end of a handle grip portion but accessible to the thumb and finger of a hand on the grip portion.

Another object of the invention is to provide an improved iron handle construction having only a single integral supporting post at the rear thereof in conjunction with a separate post at the front which resembles an integral front post but which is actually spaced from the front end of the handle grip portion.

Other objects of our invention will either be apparent from a description of one form of device embodying our invention or will be set forth in the course of such description and particularly in the appended claims.

In the drawings,

Figure 1 is a longitudinal, sectional view

2

through the center of an iron embodying our invention,

Fig. 2 is a top plan view of the indicator in the handle,

Fig. 3 is a lateral, sectional view taken on the line 3—3 of Fig. 1,

Fig. 4 is a fragmentary, vertical, transverse sectional view of the front end of the handle grip portion, and,

Fig. 5 is a top view of the front column with certain associated parts shown in section.

The novel handle construction of the present invention is shown in conjunction with an electric iron construction in accordance with our afore-mentioned application Serial No. 586,099. Such iron comprises a relatively thin metal sole plate 33, a relatively thin top plate 35 and a planar electric heating element 37 sandwiched between such plates. According to our afore-mentioned application, plates 33 and 35 are brazed together under brazing heat and high pressure at their margins to provide a thermally efficient unit. A portion 79 of brazing film which units the margins is shown in Fig. 1 adjacent heel 91 of the sole plate.

Secured in recesses in sole plate 33 and extending upwardly through the top plate are metal assembly or supporting plugs 71 and 73 located in longitudinally spaced relation at the center line of the plates. Mounted on the front plug is a U-shaped supporting bracket 143. Another differently shaped supporting bracket 125 is mounted on rear plug 73. A cover or casing 147 is provided, the lower edge of which is adapted to rest upon the outer peripheral surface of top plate 35. The rear portion of casing 147 is secured to bracket 125 by a single screw 165. A rear closure plate 167 is provided and is held by a single short screw 169 which engages the lower end of bracket 125. The further portion of the iron proper shown in Figs. 1 and 3 includes an automatically operated control switch mechanism for heating element 37. The same includes a lower contact bar 107 and an upper contact bar 121 mounted in insulated relation on rear plug 73. Contact bar 107 extends substantially longitudinally of the iron and has a contact member 127 adjacent its outer end. A coacting contact member 135 is carried by the outer end of contact bar 121. The two bars 107 and 121 are made of spring metal and biased downwardly. An upwardly biased further spring arm 115 is mounted in insulated relation on plug 73 and extends forwardly between contact bars 107 and 121, being apertured for passage therethrough of contact member 135. Through manually actuated control mechanism,

hereafter to be referred to, spring arm 115 contacts with an insulated bushing 139 mounted on contact bar 121 for adjusting the switch to cause the heating element 37 to operate at selected ironing temperatures.

The control switch is automatically operated in response to the temperature of sole plate 33 by a bimetal thermostat member 43 of sheet material and rectangular shape housed in a chamber or recess 41 in the sole plate and explained in detail in our copending application Serial No. 272,221, filed February 18, 1952. A thin metal cover 47 overlies bimetal member 43 and closes the top of chamber 41. An actuating pin 133 engages the midpoint of bimetal member 43 at its 15 lower end and engages at its upper end an insulated bushing 129 on lower contact bar 107. Pin 133 is supported by an insulated bushing 15 secured in top plate 35 and extends downwardly into chamber 41 through a hole in cover 47. The 20 opposite ends of bimetal member 43 are loosely held in position by depressed portions 51 on plate 47. Temperature changes of the sole plate cause the bimetal member to warp vertically and through actuating pin 133 to adjust the position 25 of contact bar 107.

The handle construction of the present invention includes a main handle grip portion 151 having an integral handle supporting post 153 adjacent its rear end portion and made of a heat and electric insulating material. The rear handle post or support 153 is adapted to be secured to intermediate spacing plate 155 by a plurality of short screws 157 and spacers 159. Plate 155 is adapted to be secured against a cooperating surface of casing 147 by a plurality of short screws 161, there being spacing members 163 located therebetween. The rear end portion of the handle is adapted to be held in proper position on the casing by the same single screw 165 to which, as earlier stated, secures the casing to rear bracket 125.

The structure located below the front end 152 of handle grip portion 151 is independent thereof, the handle being entirely supported through rear supporting post 153. Such structure includes a hollow front member or column 171 of the same material as the handle but formed separately therefrom. The upper end of column 171 is entirely out of engagement with the front end of handle grip portion 151 being slightly spaced therefrom, as shown in Fig. 1. Through such arrangement there is less transmission of heat from the iron body to the front end of the handle grip portion than where the handle is provided, as commonly, with an integral front supporting post.

The lower surface of column 171 has secured thereagainst a spacing plate 173 by a plurality of short screws 175 with spacers 177 therebetween. Spacing plate 173 is secured against casing 147 by a single short screw 179 which is threaded in the upper end of bracket 143.

After assembly of the iron in case it is desired to remove the handle and casing, it is only necessary to remove screw 169 as well as closure plate 167, after which removal of screws 165 and 179 permits a removal of the handle and casing and removal also of front column 171.

The handle construction described permits manual adjusting mechanism for the thermostatically operated switch in the iron body to be mounted beneath and independently of the front end of the handle grip portion and adapted for operation by the thumb and finger of a hand 75

while holding the grip portion. The independent front column 171 is adapted to serve as a housing for such manual adjusting mechanism. We have shown a manual adjusting mechanism constructed in accordance with our copending application, Serial Number 272,223, filed February 18, 1952. As more fully described therein, such mechanism includes a control shaft 183, supported in opening 181 of column 171 and the lower end of which is threaded for engaging supporting bracket 143 through an opening 149 in casing 147. The lower end of control shaft 183 engages the front end of upwardly biased spring arm 115. Rotation of shaft 183 in reverse directions causes spring arm 115 to move upwardly and downwardly. The upper end portion of control shaft 183 is splined interiorly of a hollow control wheel hub 191 for rotation therewith and axial movement independently thereof. Threaded to control wheel hub 191 and housed in a recess near the top of column 171 is a control wheel 197. Such control wheel is adapted to be rotated by the thumb and finger of a hand holding handle grip portion 151. Rotation of the wheel rotates shaft 183.

It is to be noted that the outer periphery of control wheel 197 may be provided with flutes 211 for convenience of the operator and that these flutes extend outwardly beyond the periphery of column 171 for engagement by the thumb and finger, as shown in Figs. 2 and 5.

The upper end portion of column 171 may be provided with a recess 205 through which extends a rotatable combined indicating and wheel stop member 199. Such member is splined to the upper end of wheel hub 191 and is secured thereto by a screw 203. A projection 207 is provided intermediate the ends of member 199 and a cooperating stationary stop 209 is provided in recess 205 in a predetermined position to prevent excess rotary adjusting movements by the operator turning the control wheel. Member 199 is initially secured on hub 191 so as to engage the stop when control shaft 183 causes switch contacts 135 and 127 to just engage when the iron is cold.

While member 199 is supported independently of the handle as just explained, it projects upwardly through an opening in the front end of handle grip portion 151 and a coacting stationary indicator 213 may be positioned in a recess in the upper portion of the front end of handle portion 151. Such recess is further provided with covering extensions 215 and 217 extending towards each other as shown in Fig. 4 and a transparent cover 219 is positioned in the recess thus constituted.

A pair of electric terminals 223 and 225 are secured in a recess 227 in the rear handle post 153, such recess being of substantially L-shaped. Plate 119 connects one of such terminals with contact bar 121 of the control switch and a terminal lead 229 connects the other terminal to the electric heating element 37. A single lead connects switch contact bar 107 through a further lead 109 with the heating element. A twin conductor supply cord 231 extends through handle post 153 in to recess 227 to connect with terminals 223 and 225. A spring post 233 surrounds cord 231 externally of the handle to prevent kinking. A pair of thumb rests 237 and 239 are provided at the front end of handle portion 151, thumb rest 237 being adapted for a right-handed user, while a left-handed user will use thumb rest 239.

It will be evident that the independent front column 171 may be formed and disposed in relation to the handle grip portion as to resemble a front supporting post integral with the handle. It has the advantage, however, that because of its spacing from the front end of the handle grip portion it will not conduct heat upwardly thereto. Further, column 171 may serve as a housing for a manual control mechanism for an iron control switch and support a control wheel or knob, such as 197, independently of the handle but in position to be conveniently adjusted by a hand holding the handle.

Various modifications may be made in our invention without departing from the spirit or scope thereof and all such modifications coming clearly within the scope of the appended claims are considered to be a part of our invention.

We claim:

1. An electric iron comprising an electrically heated iron body, a casing secured on said iron body, a handle of heat-insulating material having front and rear end portions and an intermediate handle grip portion, a handle support integral with the rear end portion of said handle secured on said casing and supporting the front end portion and grip portion of said handle in spaced vertical relation to said casing and an upstanding front column having its lower end secured on said casing and having its upper end portion disposed adjacent, but spaced from, said front end portion of said handle so as to avoid transmitting heat from the iron to the handle.

2. An electric iron comprising an electrically heated iron body, a casing secured on said iron body, a handle of heat-insulating material having front and rear end portions and an intermediate handle grip portion, a handle support integral with the rear end portion of said handle secured on said casing and supporting the front end portion and grip portion of said handle in spaced vertical relation to said casing, and an upstanding front column having its lower end secured on said casing and having its upper end portion underlying said front end portion of said handle in vertically spaced adjacent relation.

3. An electric iron comprising an electrically heated iron body, a casing secured on said iron body, a handle of heat-insulating material having front and rear end portions and an intermediate handle grip portion, a handle support integral with the rear end portion of said handle secured on said casing and supporting the front end portion and grip portion of said handle in spaced vertical relation to said casing, and an upstanding front column of heat-insulating material having its lower end secured on said casing and having its upper end portion in spaced adjacent relation to said front end portion of said handle, and said upper portion of said front column being formed to receive a manually adjustable rotary control member.

4. An electric iron comprising an electrically heated iron body, a casing secured on said iron body, a handle of heat-insulating material having front and rear end portions and an inter-

mediate handle grip portion, a handle support integral with the rear end portion of said handle secured on said casing and supporting the front end portion and grip portion of said handle in spaced vertical relation to said casing, and an upstanding front column of heat-insulating material having its lower end secured on said casing and having its upper end portion underlying said front end portion of said handle in vertically spaced adjacent relation, and said upper end portion of said front column being formed to receive a manually adjustable rotary control member.

5. An electric iron comprising an electrically heated iron body, a casing secured on said iron body, a handle of heat-insulating material having front and rear end portions and an intermediate handle grip portion, a handle support integral with the rear end portion of said handle secured on said casing and supporting the front end portion and grip portion of said handle in spaced vertical relation to said casing, and an upstanding front column of heat-insulating material having its lower end secured on said casing and having its upper end portion in spaced adjacent relation to said front end portion of said handle, said front column having a lengthwise extending hollow area adapted to receive an elongated adjustable control member and said upper end portion of said front column having hollow areas adapted to receive a manually adjustable rotary member for adjusting such an elongated control member.

6. An electric iron comprising an electrically heated iron body, a casing secured on said iron body, a handle of heat-insulating material having front and rear end portions and an intermediate handle grip portion, a handle support integral with the rear end portion of said handle secured on said casing and supporting the front end portion and grip portion of said handle in spaced vertical relation to said casing, and an upstanding front column of heat-insulating material having its lower end secured on said casing and having its upper end portion in spaced adjacent relation to said front end portion of said handle, said front column having a lengthwise extending hollow area adapted to receive an elongated adjustable control member and said upper end portion having a hollow area communicating with, and of greater cross section than, said lengthwise extending hollow area and adapted to receive a manually adjustable rotary member for adjusting such an elongated control member.

JOHN R. GOMERSALL,
MURRAY IRELAND.
